GASOLINE DISPENSER

David J. Nelson, Hamburg, N. Y., assignor to
 Martin & Schwartz, Inc., Buffalo, N. Y., a corporation of New York

Application June 23, 1930, Serial No. 463,126

6 Claims. (Cl. 221—95)

This invention relates to apparatus for dispensing gasoline or other liquids, and chiefly concerns the provision of locking means for locking the hose nozzle to a pump casing and simultaneously locking the control apparatus for the pump.

In the locking of gasoline dispensers a number of conditions are met with which may be overcome individually in a simple manner by multiple locking operations; however, where carelessness of employees and question of economy of time is concerned it is important to simplify such locking operations to their greatest extent. As is well known in this art, a telephone hook type of nozzle support is commonly utilized to support the nozzle of the hose when the same is in inoperative position. This support in many cases either electrically or mechanically controls the dispenser, and the weight of the nozzle on the hook actuates the same to render the pump inoperative. It will thus be obvious that upon closing a gasoline station for the night, it is extremely important to lock this member against accidental or malicious displacement. It is equally important to lock the nozzle in place, as this member is usually provided with a gasoline release trigger which controls the release valve therein. Any failure on the part of the first named release valve or control would of course permit gasoline to enter into the hose, and if the trigger were free to be moved by any one with a mischievous or malicious intent after the station has been closed, a fire hazard or at least a loss would be experienced by the station.

The hose nozzle, in addition to this, is itself a valuable piece of equipment and is easily unscrewed from the hose itself, and therefore is subject to theft. It is also deemed necessary to protect the output opening of the nozzle against the entry of water in the form of either rain or snow when the same is not in active use.

With the above enumerated conditions and requirements in view, this invention has for its object a locking means for locking the control member against manipulation, and simultaneously performing other distinct locking operations, such as locking a hose nozzle against theft, locking the trigger of the hose nozzle against manipulation, and locking the free end of the nozzle within the dispenser casing where it is protected from the elements.

These and other objects and advantages of the present invention are more specifically described and set forth in the accompanying specification and drawing.

In the drawing:

Fig. 1 is a front elevation of a gasoline dispenser diagrammatically showing the main operating units and their association to the present invention.

Fig. 2 is an enlarged cross section through the dispenser casing adjacent the hose mounting.

Fig. 3 is a section on the line 3—3 of Fig. 2.

Fig. 4 is a perspective view of the bracket.

In the specification, the numeral 1 indicates a gasoline dispenser casing or housing, within which, as is shown diagrammatically in Fig. 1, is suitably mounted a fluid pressure supply device consisting of a motor driven pump 2 which is adapted to pump liquid from the supply line 3 to the feed line 4 and from thence through the meter mechanism 5 to the flexible hose 6 through a suitable fitting in the dispenser casing. The free end of the hose is provided with a nozzle 7 which is preferably of the type shown and having a trigger 8 manually movable from the position shown in Fig. 2, to a position adjacent the nozzle to open a suitable valve therein. The nozzle is also provided with a trigger guard 9 which extends around the trigger and has an extending flat portion 10 in close proximity to the tip of the trigger. A flexible nozzle end 11 is secured to the free end of the nozzle, while the hilt end of the nozzle is shouldered at 12, for purposes hereinafter set forth. Within one wall of the casing 13 is secured in any suitable manner, and at its central portion is provided with a recess 14 which extends therethrough. A stop lug 15 is provided on the bracket immediately below and adjacent the aperture, and a pair of spaced locking members or lugs 16 immediately above said aperture. A lock hole 17 is provided in each lock lug in aligned relation. The lock lugs and the lug 15 project through to the exterior of the casing as shown in Fig. 2, while the opposite side of the bracket, also adjacent the aperture, is provided with a pair of spaced bearing lugs 18 having aligned fulcrum holes 19.

The nozzle support 20 comprises a rectangular shank 21 provided with a bearing hole 22 and a connection hole 23 at its extremity, and a bifurcated end having extending arms 23' slightly rounded upwardly and adapted to receive the shoulder 12 of the nozzle. This member is pivotally mounted between the bearing lugs 18 by the pin 23" which extends through the hole 22 thereof and the fulcrum holes 19 of the bearing lugs. The nozzle support is thus mounted in the orifice of the bracket 13 with the shank portion extending into the casing, and the bifurcated arms ex-

100

tending a distance beyond the exterior of the casing. Pivotal movement of the nozzle support in a downward direction from the position shown in Fig. 2 is prevented by the stop lug 15 which 5 immediately underlies and abuts the same.

The shank 21 of the nozzle support is connected in any suitable manner to the various control members of the pump. In the exemplary form shown in Fig. 1 a pair of connecting rods 24 and 10 25 is pivotally mounted by a clevis pin 26 through the connection hole 23. The rod 24 extends downwardly to the valve arm 25 of the control valve 27, while the rod 25 connects to the switch arm 28 of the motor control switch 29. When 15 the nozzle support is in its inoperative or locked position, (Fig. 2, full lines), the control valve 27 will be closed to prevent liquid passage between the pump 2 and the meter 5, and simultaneously the motor circuit controlled by the switch 29 will 20 be opened by the movement of the switch arm 28, thus rendering the motor of the pump inoperative. When the support is in its operative position, (Fig. 2, dotted lines), a reversal of the described action takes place, wherein the valve 27 25 and the switch are restored to their operative or working positions.

The above description of the control connections discloses but one of the many possible control combinations. It is intended that the shank 30 21 may be connected to the control members of any type of dispenser such as gravity feed, fluid pressure feed, or the hand operated type, without departing from the spirit of the invention. It will also be understood that types of nozzle supports and controls may be utilized other than the "telephone hook" specifically illustrated, the object being, however, as above set forth, to prevent operation of the fluid supply apparatus through the control means therefor when the 35 nozzle is placed on the support.

The nozzle 7 is adapted to be mounted on the nozzle support with the nozzle end 11 engaging upwardly through an orifice 30 in the casing 1 and the shoulder 12 engaging between the arms 45 23' and the flat portion of the trigger guard extending along the shank 21 to engage between the lock lugs 16. When the nozzle is thus mounted on the support, the combined weight of the nozzle and attached hose will move the support downwardly from the position shown in dotted lines to the lower position to abut the stop lug 15. When in the described lower position the trigger guard is positioned between the lock lugs 16 immediately without the line of the lock holes 17. The trigger, which is in its inoperative position is also positioned between the lock lugs and beyond the lock holes 17. The described position of the nozzle is attained by the simple operation of mounting the same on the arms 23' which properly 50 space the trigger and trigger guard for engagement with the lock lugs as described.

When it is desired to lock the nozzle to the bracket 13 the bow 31 of a padlock 32 is engaged 65 about the shank 21 of the support and through the lock holes 17 of the lock lugs thereby locking the controls in inoperative position, the trigger guard against upward movement, and the trigger against movement relative the guard. Simultaneously the nozzle end is locked against 70 removal and is protected against the elements within the casing 1.

When the padlock is removed the nozzle may be disengaged from the support and casing, subsequent to which the support may be manually 75

lifted to render the controls operative to supply the nozzle with liquid to be dispensed.

What is claimed is:

1. In a fluid dispensing apparatus, a casing, fluid supply means, control means within said casing for controlling the fluid supply means, a fluid delivery hose on the exterior of the casing in communication with the supply means, said hose terminating in a nozzle provided with a fluid release trigger, a movable supporting member connected on the interior of the casing to said control means and on the exterior of the casing being adapted to support said nozzle, and a lock receiving member on the exterior of the casing, said casing having an orifice spaced from said lock receiving member and adapted to receive the free end of the nozzle, said lock receiving member adapted to receive and cooperate with a lock to simultaneously lock said supporting member against movement to prevent movement of said control means, the trigger of the nozzle against movement to prevent release of fluid in the hose, the nozzle to the casing, said free end of the nozzle being simultaneously engaged through the orifice in said casing. 100

2. In a fluid dispensing apparatus, a casing, fluid supply means, control means within the casing for controlling said fluid supply means, a fluid delivery hose on the exterior of the casing in communication with the supply means, said 105 hose terminating in a nozzle provided with a fluid release trigger, a trigger guard enclosing said trigger, a supporting member for said nozzle extending through the casing and connected on the interior of the casing to said control means and on the exterior of the casing being adapted to support said nozzle, means on the casing pivotally mounting said support member, and lock receiving means on said last named means for receiving portions of said trigger guard, said 110 lock receiving means adapted to receive and cooperate with a lock to simultaneously lock said supporting member against movement to prevent movement of the control means, the trigger against movement in the trigger guard and the 115 trigger guard to the casing. 120

3. In a fluid dispensing apparatus, a casing, a fluid supply means, movable control means in the casing for controlling the operation of the fluid supply means, a fluid delivery hose on the 125 exterior of the casing in communication with the supply means, said hose terminating in a nozzle provided with a fluid release trigger and a trigger guard, a movable supporting member for said nozzle extending through the casing and connected on the interior of the casing to said control means and having portions on the exterior of the casing adapted to support the nozzle, and spaced lock receiving members on the exterior of said casing adapted to receive a portion 130 of the trigger guard when the nozzle is mounted on the supporting member, said locking members being adapted to receive a lock for engagement with both the trigger and said supporting member, thereby locking said control means against 140 movement, the trigger against movement to prevent the release of fluid in said hose and simultaneously locking the trigger guard and accompanying nozzle to the casing. 135

4. In a fluid dispensing apparatus, a casing, a 145 fluid supply means, movable control means in the casing for controlling the operation of the fluid supply means, a fluid delivery hose on the exterior of the casing in communication with the supply means, said hose terminating in a 150

nozzle provided with a fluid release trigger and a trigger guard, a movable supporting member connected on the interior of the casing to the control means and on the exterior of the casing 5 being adapted to support said nozzle, a bracket secured to the interior of the casing and having means for mounting said supporting member for pivotal movement, and lock receiving lugs on said bracket extending through said casing and 10 adapted to receive a portion of said trigger guard, said casing having an orifice spaced from said lock receiving lugs to receive the free end of the nozzle, said lock receiving lugs being formed to receive a lock therethrough in position to engage 15 both said trigger and said supporting member, thereby locking said supporting member against movement to prevent movement of said control means, the trigger against movement in the trigger guard, the trigger guard to the casing and 20 between said lock receiving lugs and retaining the free end of the nozzle in the orifice in said casing.

5. In combination in a fluid dispensing apparatus, a casing formed with an aperture for receiving the end of a hose nozzle to shield the same, a support for a hose nozzle on the casing adjacent the aperture, fluid supply means in said casing for supplying fluid, a hose connected to said fluid supply means and having a hose nozzle 25 connected to the free end thereof, control means associated with said casing and said supply means for controlling the fluid supply means operable to effect the flow of fluid to said nozzle when said nozzle is removed from the support, said nozzle

being provided with an operating trigger and with an open end adapted to enter said casing aperture when the nozzle is placed on the support, and lock receiving means adapted to embrace portions of the support and trigger when the nozzle is on the support to prevent operation of the fluid supply means and the trigger and the removal of the nozzle from the support and the free end of the nozzle from the aperture.

6. The combination with a fluid dispensing apparatus including a casing, fluid supply means in the casing, a hose connected to the fluid supply means and a nozzle provided with an operating trigger secured to the free end of the nozzle, of means for safeguarding the supply means and nozzle from unauthorized operation, said means comprising a bracket on the casing for effecting the hanging support of the nozzle when the same is not in use, control means for operating the fluid supply means adjacent the bracket and operable to actuate the fluid supply means when the nozzle is removed, said casing being formed with an aperture adjacent the bracket and control means for receiving the free end of the nozzle when the nozzle is in its hanging position, and means associated with the bracket for receiving locking means engaging the nozzle and trigger, whereby, upon the hanging up of the nozzle and the application of the locking means, the nozzle is secured against removal, the end of the nozzle is shielded, 105 the trigger is restrained against operation, and the control means for the fluid supply means are rendered immobile.
